CLAIM

I claim the ornamental design for a moveable storage closet, as shown and described.

DESCRIPTION

FIG. 1 is a top, front, right side perspective view of a moveable storage closet of the present Invention.

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines depict portions of the article that form no part of the claimed design.

1 Claim, 7 Drawing Sheets
